HAND MASSAGER

Samuel L. McNair, Overland Park, Kans., assignor to
Dazey Products Co., Kansas City, Mo.

Filed July 16, 1973, Ser. No. 371,737

Term of patent 14 years

Int. Cl. D28—03

U.S. Cl. D83—1 T

Fig. 1.

Fig. 2.

Fig. 3.

Fig. 4.

Fig. 5.

FIG. 1 is a top plan view of a hand massager showing my new design;

FIG. 2 is a left side view of a hand massager in FIG. 1; the opposite side is substantially the same as the side shown;

FIG. 3 is a front end view of the hand massager in FIG. 1;

FIG. 4 is a rear end view of the hand massager in FIG. 1; and

FIG. 5 is a bottom plan view of a hand massager as in FIG. 1.

I claim:

The ornamental design for a hand massager, as shown and described.
